(57) **CLAIM**

We claim the ornamental design for a mobile communications device case, as shown and described.

DESCRIPTION

FIG. 1 is a front perspective view of a mobile communications device case, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The bold broken lines along the edge of the mobile communications device case depict stitching, which is part of the claimed design. All other broken lines depict portions of the mobile communications device case that form no part of the claimed design.
